UNITED STATES PATENT OFFICE.

ADELBERT E. PARKER, OF CHICAGO, ILLINOIS.

DERRICK.

SPECIFICATION forming part of Letters Patent No. 760,557, dated May 24, 1904.

Application filed October 3, 1903. Serial No. 175,661. (No model.)

To all whom it may concern:

Be it known that I, ADELBERT E. PARKER, a citizen of the United States, residing at Chicago, in the county of Cook and State of Illinois, have invented new and useful Improvements in Derricks, of which the following is a specification.

This invention relates particularly to the revolving base or foot upon which the mast, boom, and winding-gear of a derrick are mounted and is characterized by improvements with respect to the construction thereof, as will more fully appear from the following description and claims.

15 The various parts are assembled so that they can be readily taken apart for the purpose of transportation.

In the accompanying drawings, Figure 1 is a side elevation of the apparatus, and Fig. 2 20 is a top view thereof.

Referring specifically to the drawings, the post upon which the derrick revolves is indicated at 6, conveniently made of wood and stepped to receive the metal sleeve 7, which 25 has an annular flange 8, upon which the base of the derrick rests and turns. At the top the post has a similar bearing-sleeve 9 for the upper bar of the frame of the base.

The frame of the derrick-base consists of 30 two similar castings, each of which forms one side of the base, and these are joined on a vertical median plane and held together by bolts 10. Each casting consists of upper and lower substantially horizontal bars 11 and 12, connected at the end by bars 13 and 14. The boom 15 is pivoted at 16 and fits snugly between the pieces 14, which act as side supports to prevent undue swaying or sidewise strain, while permitting the necessary vertical 35 movement. The sockets for the posts are formed between the upper and lower bars, respectively, by bosses 17, each of which has a semicircular recess to form a socket in which the post is embraced. The mast is stepped 40 in the frame beside the post on the opposite

side to the boom and fits within a socket formed between the bosses 17 and lugs 18, projecting inwardly from the upper and lower side frames. It may be readily removed, as it is found unnecessary to bolt it in place. The 50 winding-gear is mounted on the end of the frame opposite to the boom and comprises the usual drum 19, gear 20, and pinion 21, to the shaft of which a crank may be applied. The tackle 22 extends from the drum over a pulley 55 23, mortised in the mast near the foot thereof, and over a pulley 24 in the end of the boom. A guy 25 extends from the end of the boom to the top of the mast.

The construction shown has great strength 60 in proportion to the material used. The strain on the mast is applied directly to the post at two points a considerable distance apart, so there is no necessity for heavy castings. The split construction is advantageous in manufacture, and the mast and boom may be stepped in the frame either before or after it is mounted on the posts.

What I claim as new, and desire to secure by Letters Patent, is—

1. In a derrick, the combination with the post and mast, of a base-frame having upper and lower bars on each side, upper and lower sockets between the bars for the post and mast, and a boom and a winding-gear mounted on 75 opposite ends of the frame.

2. A derrick-base comprising joined side frames each having upper and lower substantially horizontal bars connected at the ends, adjacent sockets produced between the bars, 80 for the post and mast, and mountings for the boom and winding-gear at opposite ends of the frames.

In testimony whereof I have signed my name to this specification in the presence of two sub- 85 scribing witnesses.

ADELBERT E. PARKER.
